DESIGN FOR A BRUSH BACK

George Daelemans, Woodside, Long Island, N. Y., assignor to Pro-phy-lac-tic Brush Company,
Northampton, Mass., a corporation of Delaware

Application August 16, 1938, Serial No. 79,374

Term of patent 14 years

To all whom it may concern:

Be it known that I, George Daelemans, a citizen of the United States of America and a resident of Woodside, Long Island, county of Queens, State of New York, have invented a new, original, and ornamental Design for Brush Backs, of which the following is a specification, reference being had to the accompanying drawing, forming part thereof.

In the drawing:

Fig. 1 is a top plan view of a brush back showing my new design,

Fig. 2 is a side elevation, and
Fig. 3 is an end elevation.

The characteristic features of my design reside in the ornamental top portion of the brush back as best shown in Figure 1.

I claim:

The ornamental design for a brush back, substantially as shown and described.

GEORGE DAELEMANS,
